(57) **CLAIM**

The ornamental design for a collapsible bowl with tilt mechanism, as shown and described.

DESCRIPTION

FIG. 1 is a top, front perspective view of the collapsible bowl with tilt mechanism showing my new design;

FIG. 2 is a top plan view thereof;

FIG. 3 is a bottom plan view thereof;

FIG. 4 is a front-side elevational view thereof;

FIG. 5 is a right-side elevational view thereof, with the left-side elevational view being a mirror-image;

FIG. 6 is a back-side elevational view thereof

FIG. 7 is an enlarged view of the portion taken from the encircled area "7" of FIG. 2; and

FIG. 8 is an enlarged view of the portion taken from the encircled area "8" of FIG. 3; and

FIG. 9 is an enlarged view of the portion taken from the encircled area "9" of FIG. 3; and,

FIG. 10 is an enlarged view of the portion taken from the encircled area "10" of FIG. 3.

The broken lines are included for the purpose of illustrating portions of the invention and form no part of the claim.
